UNITED STATES PATENT OFFICE.

WILLIAM C. LUDWIG, OF CHILlicothe, OHIO, ASSIGNOR TO THE MEAD PULP & PAPER COMPANY, OF DAYTON, OHIO, A CORPORATION OF OHIO.

APPARATUS AND METHOD FOR PACKAGING PAPER.

Application filed January 26, 1925. Serial No. 4,899.

The present invention relates to the packaging and transporting of paper and particularly to the packaging and transporting of sheet paper adapted to be piled or formed 5 into stacks.

One of the principal objects of the present invention is to provide a novel method and apparatus for packaging and transporting sheet paper, which eliminates the damage 10 normally occurring during shipment and also makes for easier handling.

Another object is to provide such a method which involves the principle of maintaining a heavy external pressure upon the stack of 15 paper during transportation in order to prevent movement of the sheets of paper with respect to one another.

Further objects of the present invention will be apparent from the following description when taken in connection with the accompanying drawings, wherein:

Fig. 1 is a perspective view of a stack of paper packaged according to the present invention and ready for shipment;

Fig. 2 is a vertical section of the skid platform constituting the lower compression member, the section being taken on the line 2-2 of Fig. 1; and

Fig. 3 is a fragmentary perspective view 30 of a portion of the skid platform with the paper removed.

This invention is an improvement on the invention disclosed in my prior application entitled Apparatus and method for packaging paper, Serial No. 735,894, filed September 4, 1924.

Referring to the drawings, 20 denotes the sheet paper to be transported, the sheets of paper being preferably disposed horizontally and piled or formed into a stack. In contact with the upper and lower surfaces of the stack are upper and lower compression plates or members 21 and 22 respectively of substantially rigid and preferably non-yielding construction. The upper compression plate may be constructed of any suitable material such as boards extending lengthwise thereof, and includes transversely disposed channel iron bars or reinforcing members 23 which lie against the upper surface of the boards and are bolted or secured thereto in any suitable manner.

The upper and lower compression plates 21 and 22 are connected together by means 55 of clamping bolts or tie rods 24 which pass

through suitable apertures 25 in the lower compression plate and in the channel iron reinforcing member 23 of the upper compression plate 21. The tie rods 24 are provided with screw threaded nuts or other suitable fastening means whereby the compression plates 21 and 22 may be drawn together to exert any desired external pressure upon the stack of paper and to maintain such pressure upon the paper while the latter is being transported or as long as may be desired. By placing the paper under compression the friction between the sheets of paper may be increased to such an extent as to substantially prevent all slipping or movement of the sheets of paper with respect to one another and to their supporting structure. The stack of sheet paper and its supporting structure constitutes, in effect, a bale, and this bale is the shipping unit.

For the purpose of the more conveniently handling the bale or package of paper which may be of a size weighing several thousand pounds, and in order to relieve the bale of paper from racking or other strains tending to cause shifting of the paper, as far as this may be possible, the lower compression plate 22 is conveniently constructed in the form of a skid platform, the compression plate or top portion 22 thereof being spaced such a distance from the ground as to receive thereunder an elevating truck by which the bale of paper may be transported from place to place in its normal upright position.

The skid platform is of sturdy construction and consists of a pair of longitudinally disposed spaced apart angle iron strips 30 which receive and support the ends of the short lengths of boards 31. The upper surface of the boards 31 are rabbeted to receive binding strips 32, the angle iron strips, binding strips, and boards being rigidly secured together by means of bolts 33 or other suitable fastening means. Each angle iron strip 30 and its binding strip 32 constitutes what is hereinafter sometimes referred to as the side rail of the skid platform. The skid platform is provided with legs 34 of sheet metal construction, each leg having a foot portion 35 and upwardly extending leg portions 36, the upper ends of said leg portions extending along the angle iron strips or side rails and being rigidly secured thereto as 110

by welding or otherwise. It will be observed that the tie rod apertures 25 pass through the side rails or strips intermediate the leg portions 36 and when the tie rod is secured 5 in place the fastening nut is thus concealed and protected by the leg portions of the skid.

In preparing the paper for shipment it is stacked upon the skid to the desired height 10 and preferably enwrapped in a suitable protective covering, as for example thin flexible water proof paper 37, although it will be understood that the use of such protective covering may be dispensed with if desired. 15 The upper compression plate 21 and tie rods 24 are put in place and the latter are then adjusted so as to place the paper under heavy compression as already described, so as to form what is herein termed as a bale of 20 paper. A closely-enclosing confining structure is then built up upon the platform in order to protect the paper, and particularly to protect the corners or sides thereof from damage during shipment. The confining 25 structure may consist of upright confining boards or strips 38 lying against the side of the stack of paper, and similar confining strips 39 lying against the ends of the stack adjacent the corners thereof and secured to 30 the confining strips 38. The confining strips 38 and 39 may be secured to the compression members 21 and 22 as by nailing or otherwise, and the confining strips at the corners of the stack are then secured together by 35 means of suitable strap iron strips 40 as illustrated in the drawings. The end confining strips 39 preferably lie against the end edges of the skid platform or lower compression plate 22 the purpose of this being to 40 permit the packages or bales of paper to be packed in solid in a freight car the confining strips 39 of one bale being in contact with the corresponding confining strips of the next adjacent bale whereby the 45 bales are in contact with one another and with the end walls of the freight car over the entire height of the bale thus effectively reinforcing the bale and contributing to prevent any shifting of the paper which would 50 be ruinous to its quality.

From the foregoing it will be apparent that the present invention provides means whereby the paper may be readily handled for shipment or storage, the skids permitting the placing of an elevating truck underneath the skid platform or lower compression plate 22 either for loading into a freight car or for unloading therefrom. The stack or shipping unit is thus maintained in its 55 original horizontal position as it is moved from place to place and is not subject to racking strains as is the ordinary and well-known packing box which is usually raised upon one edge or tilted in order to receive a 60 truck thereunder. Also this permits of

greatly increasing the quantity of paper that may be included in a single package. An important advantage of this construction is that a number of stacks, bales or shipping units may be readily placed in position in a 70 freight car with their ends abutting against one another and against the end of the car so that the stacks support one another thereby to a large extent relieving the stacks of paper from the shocks arising during starting and stopping and moving of the train. By placing each stack of paper under suitably heavy compression alone, or by placing it under a lesser compression and abutting the ends of a number of stacks as described 75 above, it is possible to so package sheet paper that the stack will maintain its original shape and condition notwithstanding the severe shocks and rough treatment of the paper during shipment. This is an important advantage particularly in the shipment of high-grade paper inasmuch as shifting of 80 the paper would irreparably damage it.

Another advantage resides in the saving 85 in the cost of the package for the paper. As much paper may be easily handled in one package of the character herein disclosed as is ordinarily included in a considerable number of crates of the heretofore conventional character. Consequently the quantity of 90 lumber required is comparatively small, and the single package is considerably lighter in weight for any given weight of paper than in the usual form of packing cases. This results in a saving in freight charges and also 95 makes it possible to load a greater quantity of paper within a given space in a freight car.

Another advantage is the saving in the 100 handling of the paper, particularly in unpacking. Heretofore it has been customary to construct a solid packing box of the required size, to place the sheet paper therein a little at a time and finally to nail the cover thereon. Also the packing box had to be of the exact size of the paper in order to prevent undue damage during shipment. According to the present invention the paper is piled upon the platform and since the 105 platform is out in the open this may be done quickly and without damaging the edges of the sheets of paper. The stack being formed to the proper size and then covered by the protective covering, the binding and confining structure may be quickly and easily built 110 up about the stack of paper as already described. When the paper reaches its destination it may be unpacked by simply removing the confining and binding structure which leaves the stack of paper upon the 115 platform completely exposed and ready for use. As heretofore practiced considerable damage to the paper almost invariably occurred during unpacking of paper from 120 crate boxes. It is not necessary at this stage 125 130

to unpack the paper a little at a time as in the case of the ordinary packing box. Where it is desirable to season the paper prior to its use on the press, as is the case 5 of high grade paper, the paper need not be transferred from the platform to a truck, as heretofore, but may be left on the platform and placed in storage for the length of time required for proper seasoning of the 10 paper, and then withdrawn from storage as required.

From the foregoing it will be evident that the present apparatus and method of packaging and shipping paper effects a 15 great saving in wastage due to the fact that there is less handling of the paper than heretofore, and this is an item of considerable importance in the case of high grade expensive sheet paper.

20 A still further advantage resides in the fact that much material and expense may be saved by the reuse of the skid platforms, top compression plates, and the tie rods. After the paper is removed from the skid 25 platform, the latter, together with the tie rods and the top compression plate 21 may be readily returned in compact form to the shipper.

While the form of apparatus herein described constitutes a preferred embodiment 30 of the invention, it is to be understood that the invention is not limited to this precise form of apparatus, and that changes may be made therein without departing from the 35 scope of the invention which is defined in the appended claims.

What is claimed is:

1. In apparatus of the character described adapted for packaging and transporting a 40 stack of sheet paper, a top compression plate, a bottom compression plate, and tie rods connecting said compression plates and adapted to be operated to bind the sheets of paper immovably together under heavy 45 compression to prevent surface slippage thereof, said bottom compression plate constituting a skid for supporting the stack of paper spaced from the ground and comprising spaced apart side rails, means connecting 50 said side rails and forming therewith a top for the skid, supporting legs secured to said side rails, and tie rod apertures through said side rails for receiving 55 therein the lower ends of said tie rods.

55 2. In apparatus of the character described adapted for packaging and transporting a stack of sheet paper, a top compression plate, a bottom compression plate, and tie rods connecting said compression plates and adapted to be operated to bind the sheets 60 of paper immovably together under heavy compression to prevent surface slippage thereof, said bottom compression plate constituting a skid for supporting the stack of 65 paper spaced from the ground and comprising

ing spaced apart side rails, means connecting said side rails and forming therewith a top for the skid, supporting legs for the skid having foot portions and upwardly extending leg portions secured at their upper ends 70 to the side rails, and tie rod apertures through said side rails for receiving therein the lower ends of said tie rods, said apertures being disposed intermediate the upwardly extending portions of said supporting legs.

3. In apparatus of the character described adapted for packaging and transporting a stack of sheet paper, a top compression plate, a bottom compression plate, and tie 80 rods connecting said compression plates and adapted to be operated to bind the sheets of paper immovably together under heavy compression to prevent surface slippage thereof, said bottom compression plate constituting a skid for supporting the stack of paper spaced from the ground and comprising spaced apart side rails, means connecting said side rails and forming therewith a top for the skid, U-shaped supporting legs 85 for the skid having foot portions and upwardly extending leg portions of sheet metal disposed lengthwise of the rails and rigidly secured thereto, and tie rod apertures through said side rails for receiving therein 90 the lower ends of said tie rods, said apertures being disposed intermediate the upwardly extending portions of said supporting legs.

4. In apparatus of the character described adapted for packaging and transporting a stack of sheet paper, a top compression plate, a bottom compression plate, and tie rods connecting said compression plates and adapted to be operated to bind the sheets of paper immovably together under heavy compression to prevent surface slippage thereof, said bottom compression plate constituting a skid for supporting the stack of paper spaced from the ground and comprising longitudinally disposed spaced apart angle iron strips, short lengths of boards arranged laterally upon said angle iron strips, binding strips overlying the ends of said boards, means for rigidly securing said strips and boards together, and supporting legs for the skid having foot portions and upwardly extending leg portions secured at their upper ends to the side rails.

5. In apparatus of the character described adapted for packaging and transporting a stack of sheet paper, a top compression plate, a bottom compression plate, and tie rods connecting said compression plates and adapted to be operated to bind the sheets of paper immovably together under heavy compression to prevent surface slippage thereof, said bottom compression plate constituting a skid for supporting the stack of paper spaced from the ground and comprising

ing longitudinally disposed spaced apart angle iron strips, short lengths of boards arranged laterally upon said angle iron strips, binding strips overlying the ends of 5 said boards, means for rigidly securing said strips and boards together, U-shaped supporting legs for the skid having foot portions and upwardly extending leg portions of sheet metal disposed lengthwise of the 10 rails and rigidly secured thereto, and tie rod apertures through said side rails for receiving therein the lower ends of said tie rods, said apertures being disposed intermediate the upwardly extending portions of 15 said supporting legs.

6. In apparatus of the character described adapted for packaging and transporting a stack of sheet paper, a top compression plate, a bottom compression plate, and tie

rods connecting said compression plates and 20 adapted to be operated to bind the sheets of paper immovably together under heavy compression to prevent surface slippage thereof, said bottom compression plate constituting a skid for supporting the stack of 25 paper spaced from the ground and comprising spaced apart side rails, means connecting said side rails and forming therewith a top for the skid, supporting legs secured to said side rails, upright confining and 30 protecting strips closely confining the corners of the stack of paper, and a flexible binding strip encircling the stack and upright confining strips to bind the same together.

In testimony whereof I hereto affix my signature.

WILLIAM C. LUDWIG.
